UNITED STATES PATENT OFFICE

153,760

DESIGN FOR A HANDBAG

Eli Bogan, New York, N. Y.

Application July 24, 1948, Serial No. 147,745

Term of patent 7 years

(Cl. D87—3)

To all whom it may concern:

Be it known that I, Eli Bogan, a citizen of the United States of America, residing at New York, in the county of New York and State of New York, have invented a new, original, and ornamental Design in a Handbag, of which the following is a specification, reference being made to the accompanying drawing, forming a part thereof, in which

Fig. 1 is a side elevational view of a handbag embodying my new design, portions of the handle element being broken away for convenience of illustration;

Fig. 2 is an end elevational view of the handbag as shown in Fig. 1; and

Fig. 3 is a perspective view thereof on a reduced scale showing a portion of the handle omitted.

The dominant feature of my design for a handbag resides in the portions shown in full lines.

I claim:

The ornamental design for a handbag, as shown and described.

ELI BOGAN.
